UPLIFT CORSET

Joseph J. Kispert, Branford, Conn.

Application May 15, 1944, Serial No. 535,688

12 Claims. (Cl. 2-27)

This invention relates to garments and more particularly to a corset, girdle, or similar foundation garment of this type, it being one object of the invention to provide a corset so constructed and so laced that when it is worn it serves very effectively to impart uplift to the abdomen and diaphragm and imparts an improved and attractive posture to the body as well as acting as a support for internal organs and as a foundation for outer garments.

Another object of the invention is to so form the corset that it includes closure portions which are disposed over an inner vest and laced, the laces being so arranged that when they are engaged with lace-engaging members of the closure portions they are first brought downwardly in crossed relation to each other for engagement with lower ones of the lace-engaging elements and thus caused to exert upward pull when tightened and not only tighten the closure portions but also exert uplifting action which lifts the abdomen upwardly as well as inwardly and supports it very effectively.

Another object of the invention is to provide a corset wherein laces are so arranged that portions thereof may serve to tighten the vest and other portions of the same laces may then be brought downwardly in crossed relation to each other and engaged with lower ones of a series of lace-engaging members carried by the closure portions of the corset. It will thus be seen that when the laces are tied the vest and the closure portions of the corset will be subjected to equal compressing pull by the laces and even compressing pull applied thereto.

Another object of the invention is to provide the corset with laces and lace-engaging elements so arranged that the laces may be very easily engaged with the lace-engaging elements and then tightened until they apply the desired compressing and uplifting force.

The invention is illustrated in the accompanying drawings, wherein:

Fig. 1 is a front view showing a corset of the improved construction with the vest laced and the closure portions free.

Fig. 2 is a view looking at the inner face of one closure portion and vest section and showing the abdominal belt.

Fig. 3 is a transverse sectional view on the line 3-3 of Fig. 2.

Fig. 4 is a front view showing the closure portions of the corset laced.

Fig. 5 is a fragmentary perspective view of one

closure portion and vest section of the improved corset.

Fig. 6 is a front view of a corset having a modified construction.

Fig. 7 is a view similar to Fig. 6, showing the closure portions laced.

Fig. 8 is a perspective view of a portion of the corset shown in Fig. 6.

Fig. 9 is a front view of another modified form of corset.

Fig. 10 is a view showing the corset of Fig. 9 laced.

Fig. 11 is a perspective view of a portion of the corset shown in Fig. 9.

Fig. 12 is a sectional view on the line 12-12 of Fig. 11.

Fig. 13 is a fragmentary view looking at the front of another modified form of corset.

Fig. 14 is a sectional view on the line 14-14 of Fig. 13, with the laces omitted.

Fig. 15 is a front view showing the corset of Fig. 13 partially laced.

Fig. 16 is a fragmentary view showing the corset of Fig. 13 fully laced.

Fig. 17 is a fragmentary perspective view illustrating the manner in which the laces of Fig. 13 are applied to the closure portions after tightening the vest.

The garment illustrated in Figs. 1 through 5 of the drawings, may be referred to as a girdle or corset and has a body 1 which fits about a person's waist and hips, as shown in Fig. 1. The body has been shown open along its front, but it is to be understood that the opening may be

35 at the back of the corset or along a side thereof. Along its open front, the girdle has closure portions 2 having reinforcing hems or stays 3 along their free side edges. Eyelets 4 are mounted

40 3 to receive laces 5 and 6 and between the eyelets and their upper ends the stays carry a series of lace-engaging hooks 7 which may be of any suitable type and project from the stays in order that they may be readily engaged by laces.

45 The closure portions 2 overlie a vest consisting of companion sections 8, each of which consists of a vertically extending marginal portion or stay 9 carrying fasteners 9' and a plurality of horizontally extending webs or strips 10. While the

50 upper web of each vest section has been shown formed of elastic fabric and the others of non-elastic fabric, it will be understood that they may all be elastic or non-elastic, and the arrangement of the webs may be varied. Abdominal bands 11 are associated with the vest sections and may be

referred to as lower portions thereof since they extend transversely of the vest sections below the webs 10 and have their outer ends seamed into the inner edges of the stays or vertically extending portions 9 of the vest sections. The abdominal bands are of greater length than the width of the vest sections and each has its inner end sewed into a stay 12, the stays 12 being spaced from the marginal stays 13 into which inner ends of the webs 10 and inner side edges of the closure portions 2 are sewed. The outer portions or sections 14 of the abdominal bands are formed of thinner and softer fabric than their inner portion so that they may be folded without uncomfortable bulk when the abdominal bands are subjected to compressing stresses and gathers or folds formed in the portions 14.

Each abdominal band is provided with strips 15 and 16 of strong fabric which extend vertically, the strips 15 being sewed into the seams 17 which connect the thin outer sections of the bands 11 with the thicker inner sections thereof and the strips 16 being sewed into inner edges of the stays 9 between the webs 10 and lower ends of the stays. These strips carry eyelets 18 to receive laces 19 which are quite long and are threaded upwardly back and forth through the eyelets and between free side edges of the strips. A knot 20 may be formed at the lower end of each lace 19 to prevent it passing through the lower eyelet of strip 16 but it will be understood that, if desired, this end of the lace may be sewed into or against the lower end of the strip 16.

When this corset or girdle is worn, it is applied about the wearer's waist and hips and the fastener members 9' of the vest sections engaged with each other. The laces 19 are then tightened to draw the strips 15 and 16 toward each other and, as they are tightened, the soft sections 14 of the abdominal bands will be crinkled into flat folds and no lumps formed such as would be uncomfortable. By reason of the upward direction of the lacing and the staggered position of the eyelets in the strips 15 and 16, a lifting action will be exerted on the portion of the vest section adjacent the strips 16. After the laces have been tightened, they are brought downwardly in crossed relation to each other and, since lower ones of the hooks 7 are at approximately the level of the lower ends of the strips 15 and 16, the laces will be engaged with the hooks at about the level of the lower edges of the abdominal bands. Referring to Fig. 4, it will be seen that the lace 19 at the right side of the vest is engaged with the hook of the left hand closure portion 2 and the lace at the left side of the vest is engaged with the hook at the right hand closure portion. After the laces 19 are engaged with the lower ones of the hooks 7, they are brought upwardly back and forth between the closure portions and successively engaged with the remainder of the hooks, and a bow-knot formed at the upper ends of the closure portions. Since the laces 19 extend downwardly from the upper ends of the strips 15 to the lower ones of the hooks 7, upward pull will be exerted by the tightened laces and the lower end portions of the closure portions 2 will be drawn upwardly as they are drawn toward each other. Therefore, a person wearing the girdle will be subjected to an uplift action which uplifts and flattens the abdomen. The diaphragm is also raised and the chest and bust extended. After the laces 19 have been knotted at the upper ends of the closure portions, the laces 5 and 6 are threaded through the eyes 4 and

tied and, since the lower portions of the stays or binds for the closure portions are soft and flexible, a close fit may be established and a good support for the lower portion of the abdomen provided.

It will thus be seen that the improved girdle or corset is so formed that when it is applied and the laces tightened, the abdomen will be flattened and an uplifting action applied to the abdomen, as well as the diaphragm. It will also be noted that the entire corset is tightened about the person wearing the same and a snug, smooth fit obtained about the waist and hips. Particularly attention is called to the fact that, due to the location of the strips 15 and 16 with respect to the lace-engaging hooks, and the fact that the laces 19 are threaded upwardly through the eyelets 18 to the upper ends of the strips, the laces may be brought downwardly diagonally in crossed relation to each other before being engaged with the lower ones of the hooks 7 and create the uplifting force when tightened. This diagonal disposition of the laces in crossed relation to each other is a very important element of the invention as it is due to this that the uplift action is attained.

In Figs. 6 through 8, there has been illustrated a corset or girdle of modified construction. In this embodiment of the invention, the garment has a body 21 which has been shown open along its front and is provided with vest sections 22 and closure sections 23 which overlie the vest sections when closed. Each vest section or portion has a thick outer or forward portion 24 and a thin inner portion 24' which is sewed to the companion outer portion, and inner or rear side edges of the inner portions 24' are secured by seams at the junction of the body with the closure portions 23. There have also been provided strips 25 sewed into the seams at the junction of the body with the closure portions and the vest sections, and these strips carry eyelets 26 spaced from each other longitudinally thereof. The strips 25 extend the full length of the corset body, as do also the closure portions 23, but the vest sections are shorter and terminate in spaced relation to the lower ends thereof. The portions 24 of the vest sections are preferably reinforced by stays and carry fastener members 27 along their free side edges. Tapes 21 extend transversely across the closure sections and the portions 24' of the vest sections with their ends sewed into outer margins of the closure portions and into seams at the junction of the portions 24 and 24' of the vest sections and their intermediate portions threaded through the eyelets 26. By this arrangement, pull exerted upon the outer portions of the tapes will act upon the strips to draw them forwardly and fold the soft rear portions 24' of the vest sections so that a smooth fit is obtained when the closure portions are drawn tightly to closed position. The closure portions are drawn toward each other to closed position by laces 28 which are sewed into inner or rear margins of the portions 24 of the vest sections below the lowest tapes and these laces are passed upwardly through eyelets 29 carried by the strips 25 and located between lower ones of the eyelets 26. It will thus be seen that the eyelets 29 are located upwardly from the lower ones of the tapes and that when the girdle is applied and the fasteners 27 of the vest sections engaged with each other to secure the vest closed, the laces on first being tightened will exert an upward pull on the vest sections and then may be brought

diagonally downward in crossed relation to each other, as shown in Fig. 7, and then passed back and forth through loops formed by the tapes and tied at the top of the girdle. As the laces are tightened they exert upward pull at their lower ends and at their points of engagement with the lowest tapes and this causes uplift to be applied to the abdomen as well as compressing action. After the laces 28 have been tightened, the soft lower end portions of the closure portions are drawn tightly to closed position by laces threaded back and forth through eyelets 30 and then tied. The girdle when worn and so secured is very comfortable and since it applies uplift as well as compressive action, the abdomen and diaphragm will be well supported and a good posture imparted to the person wearing the girdle.

The form of girdle or corset illustrated in Figs. 9 through 12, also has a body 31, vest sections 32, and closure portions 33. Each vest section has a forward marginal portion 34 carrying fasteners 35 and horizontal strips or webs 36, the upper and lower ones of which are preferably formed of elastic fabric. Inner or rear ends of the webs 36 are sewed into seams 37 which also connect the closure portions with the body of the girdle and between the inner side edge portions of the vest sections and the closure portions are mounted short strips 38 carrying eyelets 39 near their upper and lower ends. Companion strips 40, which are shorter than the strips 38, are mounted between the marginal portions or strips 34 and outer ends of the webs 36 and carry eyelets 41 located in a plane between the eyelets 39. While the strip 40 has been shown carrying one eyelet 41 and the strip 38 carrying two eyelets 39, it will be understood that additional eyelets may be provided, it being important, however, that the strips 38 extend above the strips 40 and have their upper eyelets above the plane of the upper eyelets 41 of the strips 40. Laces 42 are secured at the lower ends of the strips 40 and passed back and forth through eyelets 39 and 41. When pull is exerted thereon, the strips will be drawn toward each other to constrict the girdle about the wearer's waist and hips. After the strips have been drawn toward each other the laces are extended downwardly diagonally in crossed relation to each other and engaged with lower ones of hooks 43 mounted in and protruding from outer side edges of the closure portions and then extended upwardly back and forth in engagement with the hooks until the upper ones of the hooks are reached, the laces then being tied in a bow-knot. Since the laces extend downwardly from the upper ends of the strips 38 to the lower ones of the hooks 43, tightening of the laces will cause upward pull to be exerted and the abdomen will be subjected to uplifting action as well as constricting pressure and the diaphragm and abdomen very effectively supported and a good posture imparted to the wearer. Below the hooks 43, the closure portions 33 carry eyelets 44 through which a lacing 45 is threaded and when this lacing is tightened and tied, the lower portions of the closure portions will be firmly held in place against the lower portions of the vest sections.

Figures 13 through 17 illustrate another embodiment of the invention wherein the body 46 of the girdle has closure portions 47, one of which is preferably formed integral with the body and the other being formed separate from the body and having a soft inner side portion carrying a strip 48 to which are sewed a number of hooks 49 for engaging eyes 50 which are sewed along 75

an edge of the body 46. The side edge of the body to which the eyes are sewed also carries a soft strip 51 which projects therefrom and serves as a shield for the hooks and eyes. This is clearly shown in Fig. 14 and, referring to this figure, it will be seen that by releasing the hooks the girdle may be removed without disturbing the laces carried by the closure portion 47.

The vest 52 is formed of soft fabric but reinforced midway its width by relatively thick fabric strips 53 which are sewed to the vest against inner and outer surfaces thereof. Side edges of the vest are sewed into inner side edge portions of facing strips 54 which are sewed against inner surfaces of the closure portions to reinforce the same and adjacent outer marginal side edges of the closure portions are eyelets 55 for receiving laces. Strips 56 and 57 are sewed into inner side edge portions of the facing strips 54 and opposite side edge portions of the outer fabric strip 53 and these strips are spaced upwardly from the lower end of the vest and carry lace-receiving eyelets 58.

When this form of girdle is worn, it is applied about the wearer's waist and hips and the hooks 49 engaged with the eyes 50. Laces 59 are then threaded back and forth through the eyelets 58 of the companion strips 56 and 57, starting at the lower ends of the strips 57, and tightened to draw the companion strips toward each other, after which the laces are brought downwardly diagonally in crossed relation to each other and passed through eyelets of the closure portions which are located slightly below the lower ends 35 of the strips 57. The laces are then brought upwardly and threaded back and forth through eyelets of the closure portions to a point adjacent upper ends of the strips 56 and 57 and tied in a bow-knot. Since the laces extend downwardly 40 from upper ends of the strips 56, upward pull will be exerted when the laces are tightened and uplifting action will be applied to the abdomen as well as constricting effect being applied to the girdle. Laces 60 and 61 are then threaded 45 through eyelets of the closure portions and tied after being tightened, the lace 60 being threaded through eyelets 55 below the laces 59 and the lace 61 being threaded through eyelets 55 between the laces 59 and the upper ends of the closure portions.

When the girdle is to be removed, the laces 59 are released but the laces 60 and 61 may be left tied as the hooks 49 are disengaged from the eyes 50 and this releases the closure portion carrying the hooks from the adjoining side edge of the body of the girdle and permits free removal of the girdle. When the girdle is again put on, the hooks are re-engaged with the eyes and the laces 59 again tightened to exert constricting and uplifting pull and tied together in a bow-knot.

I have, therefore, provided a girdle or corset including closure portions disposed over a vest and a special arrangement of laces for drawing the garment snugly into place about a person, the laces being so arranged in all embodiments of the invention that when they are tightened, uplifting force will be applied to the abdomen as well as constricting force. Therefore, the diaphragm and abdomen will be urged upwardly and be well supported and a good posture imparted to the figure of the person wearing the girdle.

Having thus described the invention, what is claimed is:

1. A garment comprising a body having closure

portions and a vest, said closure portions extending from opposite sides of the vest toward each other in overlying relation to the vest when closed, lace-engaging members along free side edges of said closure members, lace engaging members carried by said vest and so arranged that upper ones of the lace engaging members of the vest are above lower ones of the lace engaging members of the closure portions, and laces laced upwardly in engagement with the lace engaging members of said vest and then brought diagonally downwardly in crossed relation to each other and laced upwardly back and forth in engagement with lace engaging members of the closure members and secured, the diagonally extending portions of the tightened laces exerting uplifting pull upon the closure portions.

2. A garment comprising a body having closure portions and a vest overlapped by the closure portions, lace engaging members carried by the vest and closure portions, and laces laced upwardly in engagement with lace engaging members of the vest and tightened and then brought downwardly in diagonally extending crossed relation to each other and laced upwardly in engagement with the lace engaging members of the closure portions and tightened to constrict the garment about a person with the diagonally extending portions of the laces exerting upward pull to compress and uplift a person's abdomen.

3. A garment comprising a body having a vest and closure portions extending toward each other in overlying relation to the vest when closed, and laces for the vest and closure portions adapted to constrict the garment about a person and having portions extending diagonally in crossed relation to each other between the vest and closure portions for exerting upward pull upon the closure portions imparting uplift to a person's abdomen.

4. A garment comprising a body having a vest and closure portions extending toward each other in overlying relation to the vest when closed, lace engaging members along free side edges of said closure portions, strips carried by said vest, said strips being spaced from each other transversely of the vest and provided with lace engaging members, and laces laced upwardly back and forth between said strips in engagement with the lace engaging members and then brought downwardly diagonally and laced upwardly back and forth between lace engaging members of the closure portions and tightened to constrict the garment with said diagonally extending portions of the laces exerting upward pull to impart uplift to a person's abdomen.

5. A garment comprising a body having a vest and closure portions extending toward each other in overlying relation to the vest when closed and provided with lace-engaging members, strips spaced from each other transversely of the vest and having lace-engaging members adjacent free side edges, and laces laced upwardly back and forth between the lace-engaging members of said strips and then extending downwardly in diagonal crossed relation to each other to approximately the level of the lower end of the vest and laced upwardly back and forth between the lace-engaging members of said closure portions and tightened and secured to constrict the garment about a person and exert pull upon the diagonally extending portions of the laces to uplift a person's abdomen.

6. A garment comprising a body having a vest and closure portions extending toward each other in overlying relation to the vest when closed and

provided with lace-engaging members, said vest consisting of companion sections secured along inner side edge portions to the body and having interengaging fasteners along meeting outer side edges, strips spaced from each other transversely of the vest sections and secured thereto and provided with lace-engaging members, and laces laced back and forth between lace-engaging members of said strips and then extending downwardly in diagonal crossed relation to each other and laced upwardly back and forth between the lace-engaging members of the closure portions.

7. A garment comprising a body having a vest and closure portions extending toward each other in overlying relation to the vest when closed and provided with lace-engaging members, strips spaced from each other transversely of the vest and having lace-engaging members adjacent free side edges, and laces laced upwardly back and forth between the lace-engaging members of said strips and then extending downwardly in diagonal crossed relation to each other to approximately the level of the lower end of the vest and laced upwardly back and forth between the lace-engaging members of said closure portions and tightened and secured, and other laces laced back and forth between the closure portions below the first laces to constrict the lower portion of the garment independently of the constricting and uplifting action of the first laces.

8. A garment comprising a body having a vest and closure portions extending toward each other in overlying relation to the vest when closed and provided with lace-engaging members, said vest consisting of companion sections secured along inner side edge portions to the body and including abdominal bands, means for releasably connecting outer side edges of the vest sections with each other in closed position, strips sewed vertically across the abdominal bands and having free side edges spaced from each other and provided with lace-engaging members and laces laced back and forth between the lace-engaging members of said strips and extending downwardly from upper ends of the strips diagonally in cross relation to each other and laced upwardly back and forth between lace-engaging members of said closure portions and secured with the diagonally extending portions of the laces exerting upward pull to the closure portions for imparting uplift to a person's abdomen.

9. A garment comprising a body having a vest and closure portions overlying the vest when closed, said vest consisting of companion sections having free side edges provided with interengageable fasteners for holding the vest closed, strips extending vertically and secured between inner edge portions of the vest sections and the closure portions, eyelets carried by said strips, tapes slidably passing through said eyelets and extending transversely of the vest sections and closure portions and secured at their ends to the vest sections and outer side edges of said closure portions, other eyelets carried by said strips and spaced upwardly from lower ones of said tapes, and laces secured to said vest sections below the lowest tapes and carried upwardly and threaded through the second mentioned eyelets and then extending downwardly therefrom in crossed relation to each other and laced upwardly back and forth in engagement with loops formed by outer end portions of the tapes and secured.

10. A garment comprising a body having a vest and closure portions overlying the vest when closed, said vest consisting of companion sec-

tions having free side edges provided with inter-
engageable fasteners for holding the vest closed,
strips extending vertically and secured between
inner edge portions of the vest sections and the
closure portions, eyelets carried by said strips,
tapes slidably passing through said eyelets and
extending transversely of the vest sections and
closure portions and secured at their ends to the
vest sections and outer side edges of said closure
portions, other eyelets carried by said strips and
spaced upwardly from lower ones of said tapes,
and laces secured to said vest sections below the
lowest tapes and carried upwardly and threaded
through the second mentioned eyelets and then
extending downwardly therefrom in crossed rela-
tion to each other and laced upwardly back and
forth in engagement with loops formed by outer
end portions of the tapes and secured, and eyelets
carried by free outer side edges of the closure por-
tions between their lower ends and said tapes
whereby lower end portions of the closure por-
tions may be constricted by laces threaded through
the last mentioned eyelets.

11. A garment comprising a body having a vest
and closure portions overlying the vest when
closed, said vest consisting of companion sections
each having a vertical strip constituting an outer
side edge portion and having horizontal strips ex-
tending from the vertical strips and secured at
inner edges of said closure portions, interengag-
ing fasteners carried by the vertical strips for
holding the vest sections closed, opposed strips
mounted at inner side edges of the vertical strips

5
10
15
20

30

and at the junction of the horizontal strips with
inner side edges of said closure portions, eyelets
carried by the opposed strips, lace-engaging hooks
at outer side edges of said closure portions, and
laces secured adjacent lower ends of the strips
carried by said vertical strips and laced upwardly
back and forth through the eyelets of the opposed
strips and then extending downwardly in crossed
relation to each other and laced upwardly back
and forth in engagement with said hooks and
secured at upper ends of the closure portions.

12. A garment comprising a body having a vest
and closure portions overlying the vest when
closed, said vest consisting of companion sections
each having a vertical strip constituting an outer
side edge portion, inner side edges of the vest sec-
tions being secured along inner side edges of the
closure portions, opposed strips secured along
inner side edges of the vertical strips and between
inner side edges of the vest sections and the clos-
ure portions and provided with lace-engaging
members, lace-engaging members carried by outer
side edges of said closure portions and laces se-
cured at lower ends of the strips carried by the
vertical strips and laced upwardly back and forth
between the opposed strips in engagement with
the lace-engaging members thereof and then ex-
tending downwardly from upper ends of the strips
at inner ends of the vest sections in crossed rela-
tion to each other and laced upwardly back and
forth between the lace-engaging members of the
closure portions.

JOSEPH J. KISPERT.
